UNITED STATES PATENT OFFICE.

LENA BELLE PROUT, OF MORLAND, KANSAS.

SOUND AMPLIFIER FOR TALKING MACHINES.

Application filed December 27, 1921. Serial No. 525,206.

To all whom it may concern:

Be it known that I, LENA BELLE PROUT (Mrs. JAMES EARNEST PROUT), a citizen of the United States of America, residing at 5 Morland, in the county of Graham and State of Kansas, have invented a new and useful Improvement in Sound Amplifiers for Talking Machines, of which the following is a specification.

10 My invention is an improvement in those sound amplifiers for talking machines which are used in connection with sound recording and reproducing machines.

The object of my invention is to provide 15 sound amplifiers for talking machines with an improved construction of lining which will eliminate all harsh, metallic and unnatural sounds which occur in existing types of sound amplifiers of sound recording and 20 reproducing machines.

My invention consists in the novel features of construction of the lining of the sound amplifier for talking machines hereinafter described and claimed.

25 In order that my invention may be fully understood I will proceed to describe it in connection with the accompanying drawings in which similar reference numerals indicate corresponding parts in the different 30 views.

Figure 1 is a perspective view of a modern form of talking machine, the doors of the tone chamber being open and showing my improved sound amplifier located within 35 the tone-chamber thereof;

Figure 2 is a vertical section taken on the line 2—2 of Figure 3 looking in the direction of the arrows.

Figure 3 is a horizontal section taken on 40 the line 3—3 of Figure 2 looking in the direction of the arrows.

Figure 4 is a detail transverse section on a larger scale of my improved amplifier having layers of wood material arranged with 45 the grain thereof crossed.

Figure 5 is a detail longitudinal section of the lining showing a modification in the construction of the extended covering for the solid layers.

50 1 represents a modern form of talking machine provided with a tone-chamber 2 within which is located my improved sound amplifier 3. This amplifier is of usual form having a neck 4, provided with a throat 5, 55 leading to the body 6 having a flaring mouth 7. It is to the construction of this ampli-

fier that my invention is directed and especially to the formation thereof, the size and shape not being material to the spirit of this invention. The amplifier is fitted 60 removably within the tone-chamber of the machine so as to be readily placed therein and easily withdrawn therefrom, but may be solidly attached to the tone chamber by proper adhesives or other material without 65 departing from the spirit of this invention, and is made up of alternately arranged layers of solid material, such as wood, plastic materials, or metal, or a combination of wood, plastic materials and metal, and 70 layers of textile material, such as velvet or felt. 8 and 9 are layers of wood material arranged with the grain thereof crossed or other solid material, as above described and 10, 11 and 12 are layers of textile fabric 75 which alternate with, are fitted closely to, completely cover and separate the layers of solid material. One or more of these layers of solid material may be employed in making the structure. Two layers of solid material 80 are shown in the present instance. 10 is the intermediate layer of textile fabric placed between the layers of solid material, and 11 and 12 are respectively the inner and outer layers of textile fabric. The 85 layers of solid material and the layers of textile fabric are secured together by suitable adhesive material. The outer layer 12 of textile fabric provides a textile surface to the amplifier between the amplifier and 90 the tone-chamber.

The inner layer of textile fabric is extended beyond the forward end of the body of the amplifier and folded outwardly and then rearwardly to provide laps 13, which 95 are turned back so as to occupy a position between the body of the amplifier and the tone chamber and spaced from the body so as to form pockets 14 for a padding 15, thus furnishing a padded cushion between 100 the amplifier and the wall of the tone chamber. In a similar manner the rear end of the amplifier is cushioned by extending the inner layer of textile fabric upwardly through the throat 5, above the neck 4 and 105 folding it outwardly to provide laps 15^a which are spaced from the top of the neck 4 and turned down so as to occupy a position over the neck 4 between the neck 4 and the tone-chamber 2, and form pocket 16, 110 for a padding 17 thus furnishing a cushion between the amplifier and the wall of the

tone-chamber at the top of the tone-chamber. In Fig. 5 I have shown a modification in the form of the cushion lap 15 for the ends of the lining. The cushion-lap in this 5 instance is made of a separate piece of textile fabric folded into inverted U-shape in transverse section and thus provides a cap piece 18 forming a pocket 19 for a padding 20 to furnish a cushion between the neck of 10 the amplifier and the top of the tone-chamber. 21 is an angular corner padding beneath and in rear of the inner end of the body of the amplifier and provides a supporting cushion and a spacing cushion at 15 this place and may be secured to the sound amplifier by adhesive material so as to form a part of the amplifier. The inner layer 11 of textile fabric at the base of the throat of the neck of the amplifier is curved away 20 from the corner at the base of the neck to provide a triangular pocket 22 for a padding 23. The direction of the sound currents passing through the throat and mouth of the amplifier are indicated by the large 25 winged arrows shown in Figure 2.

Having thus described my invention the following is what I claim as new therein and desire to secure by Letters Patent:

1. A sound amplifier for talking machines comprising a layer of solid material, a layer 30 of textile fabric fitting closely to and completely covering the layer of solid material, extending around the forward end of the

body of the amplifier and folded outwardly and rearwardly thereagainst so as to form 35 a pocket and padding in said pocket providing a cushion for the amplifier.

2. A sound amplifier for talking machines comprising a layer of solid material, a layer of textile fabric fitting closely to, completely 40 covering the layer of solid material, extended beyond the forward end of the body of the amplifier and folded outwardly and rearwardly thereagainst so as to form a pocket and padding in said pocket providing 45 a cushion for the amplifier.

3. A sound amplifier for talking machines comprising a layer of solid material forming the body, neck and throat of the amplifier, a layer of textile fabric, fitting closely 50 so as to completely cover the layer of solid material extended beyond the upper end of the neck of the amplifier so as to form a pocket and padding in said pocket providing a cushion on the top of the neck around 55 the throat for the amplifier.

4. A sound amplifier for talking machines comprising a layer of solid material forming the body, neck and throat of the amplifier, a layer of textile fabric completely covering 60 the layer of solid material, the layer of textile fabric being curved inwardly away from the corner of the throat forming a pocket, and padding located in said pocket.

LENA BELLE PROUT.
(MRS. JAMES EARNEST PROUT).
